UNITED STATES PATENT OFFICE.

RALPH L. SKINNER, OF DETROIT, MICHIGAN, ASSIGNOR TO SKINNER AUTOMOTIVE DEVICE CO., INC., OF DETROIT, MICHIGAN, A CORPORATION OF CALIFORNIA.

INTERNAL-COMBUSTION-ENGINE LUBRICATION SYSTEM.

Application filed August 7, 1926. Serial No. 127,813.

I have heretofore invented and patented a lubrication rectification system for internal-combustion engines wherein fluids are withdrawn or removed from circumferential grooves around the engine pistons through ports in the engine cylinder side-walls with which such grooves and extensions thereof disposed longitudinally of the pistons come intermittently or interruptedly into register, 5 such abstracted, impure oil being rectified or freed from its polluting constituents in a suitable separator or purifier wherein the contaminated lubricant is subjected to sub-atmospheric pressure and, preferably, also 10 simultaneously to heat, the reclaimed oil being returned to the engine crank-case for reuse.

Such appliances, formerly, have required extensions on the skirts of the pistons in 20 register with and designed to cover the cylinder wall ports when the piston skirts during their upward movements ascended beyond the ports, as otherwise the latter would be uncovered, and, in those instances, where 25 the suction existing in the engine intake-manifold is employed to withdraw the fluids, including the oil, from the piston grooves through the cylinder ports into the rectifier or purifier, the carburation or gaseous mixture in the manifold would be interfered with and disadvantageously affect the smooth 30 and proper running of the motor.

Such piston skirt extensions or narrow 35 prolongations have certain objections, in some cases, and I have discovered that these parts of the pistons may be left off or eliminated, provided the one or more passages through the conduit or conduits connecting the cylinder ports to the purifier are made 40 small enough and yet of sufficient size, and the cylinder ports thus protected may be permitted to be uncovered or unclosed by the pistons during portions of the strokes of the latter without encountering detrimental results.

The same general plan of construction 45 may also be used to advantage in Knight-type of engines in which each cylinder has one or more ported movable sleeves controlling the intake of the gaseous mixture and the delivery or discharge of the exploded 50 gases.

To enable those skilled and trained in this 55 art to understand the invention and its resulting advantages, I have shown it applied

to both styles of engines in the accompanying drawings forming a part of this specification, and throughout the several views of which like reference characters have been employed to designate the same structural 60 parts.

In these drawings:

Figure 1 is a fragmentary, sectional view through one cylinder of a multi-cylinder internal-combustion engine of the poppet-valve type fitted with the new system incorporating the present invention; 65

Figure 2 is an enlarged, small section through the cylinder port and the adjacent portion of the piston; 70

Figure 3 is a similar fragmentary section through the opposite part of the piston showing the air-inlet or bleeder port for the piston oil groove;

Figure 4 is a vertical section through one cylinder of a Knight engine showing the invention applied thereto; 75

Figure 5 is an enlarged, fragmentary section through the inner sleeve and the adjoining part of the piston; 80

Figure 6 is a similar section through the opposite part of the piston showing the air-admission opening for the piston oil groove;

Figure 7 is a face view of the metered hole through the inner sleeve and its enlarged entrance; and 85

Figure 8 is a face view of the elongated slot through the outer sleeve.

Referring first to the species shown in Figures 1, 2 and 3, it will be perceived that 90 the water-jacketed cylinder 11 accommodates the reciprocating piston 12 with which the usual connecting-rod 13 is rockingly associated in the customary manner, the engine having a fuel-intake-manifold 14 95 joined to the carburetor, (not shown), and an exhaust-manifold 15, the exhaust-valve 16 being illustrated, but the inlet-valve for the cylinder is not depicted.

As is more clearly shown in Figures 2 and 100 3, the piston 12 has a shallow, horizontal, circumferential, oil-collecting groove 17 around its periphery at any convenient location, but preferably, as in the present instance, between two of the usual piston-rings 105 18, 18, such groove or channel 17 at one point having a small, air-inlet port or passage 19 extended inwardly therefrom through the piston wall to its hollow interior, whereby the groove 17 is in commun- 110.

cation with the interior of the engine crank-case through the piston.

Directly opposite such bleeder or vacuum-relief port 19, the cylinder-wall is provided 5 with a threaded hole or port 21 there-through in which is fitted an angular-headed screw 22 which holds in place, between its head 23 and the adjacent surface of a boss 24 cast integral with the cylinder wall 11, 10 a flattened tubular manifold 25, which is common to and similarly connected to all of the engine cylinders.

Washers or gaskets 26 and 27 are positioned on opposite sides of the manifold, as 15 is fully illustrated.

Screw 22 has a cross hole 28 extended through it at a position to connect at both ends with the interior of the manifold and at its middle with a lengthwise central passage 29 in the screw.

Such screw at the end of passage 29 is fitted with a plug 31 held firmly in place by friction in the cavity 29 and supplied with a carefully metered small hole or port 25 32 therethrough which establishes communication between a conical or flaring mouth or entrance 33, provided in the end of the screw and plug for a purpose hereinafter indicated, and the passage 29.

Such port 21, through the side-wall of the cylinder, is so located, that, as the piston approaches, passes, and recedes from its lower dead-center, its oil groove 17 will be in communication with the port 21 for a 35 substantial period of time, in the present instance, a period representing the turning of the engine crank-shaft through about 35 degrees.

The manifold 25 is connected by a pipe or 40 tube 34 to a passage 35 in the horizontal, division wall 36 of an oil purifier or rectifier of known construction having above the division-wall a separating or vaporizing chamber 37 formed by a shell 38 and below 45 the division-wall an oil-storage compartment 39 formed by an externally ribbed or finned shell 41.

This partition-wall 36 has a central passage 42 connected by a tube 43 to the intake-manifold, whereby the rectifier and its connections are subjected to subatmospheric pressure.

The interior of the rectifier is supplied with baffles 44, 45 and 46 and the division 55 wall is equipped with ports, valves, thermostat etc., while the lower chamber has a float 47 connected to operate the valves in known manner, the lower part of the storage-compartment having a discharge-pipe 48, fitted 60 with a ball check-valve 49, for delivering the reclaimed oil intermittently back to the engine crank-case, without interrupting the continuous suction in the upper vaporizing or rectifying chamber 37, the latter being 65 heated to aid the gasification of the volatil-

izable ingredients of the impure oil by a portion of the hot exhaust gases of the engine flowing through a jacket 51 surrounding or encasing the upper portion only of the rectifier.

This rectifier is of well-known structure and is now on the market so that its details need not be presented here.

The operation of the appliance is substantially as follows:

During that period of time that the piston-groove 17 is in register with the cylinder-port 21, the suction exerted through pipe 34 and the rectifier withdraws the liquid and gaseous contents of such piston channel, which action is facilitated by the air entering the groove through the air-port 19, so that the oil in the piston groove, rendered more or less impure by some of the fuel in liquid or gaseous form and some of the products of combustion which reach the groove in their downward passage around the piston, is aerated and delivered into the rectifier where the oil is purified under heat and suction by being freed from its volatile ingredients which flow from the rectifier into the intake-manifold and are consumed in the engine.

The reclaimed or purified oil passes down into the storage-compartment of the rectifier from which it is discharged automatically interruptedly into the crank-case.

For a part of the time the cylinder-port 21 is closed by the skirt of the piston and for a portion of the time such port is uncovered due to the piston skirt passing upwardly beyond it.

No harm results from such free opening of the port because the metered hole 32 is of such size that the air passing there-through is sufficiently small in volume as not to upset the carburetion.

During the running of the engine, oil accumulates in the enlarged or conical entrance 33, and, when the piston uncovers the cylinder-port, this oil is drawn through the metered hole or aperture, but due to the resistance which such oil encounters in flowing through such a small hole, no excessive amount of air is permitted to pass through with it.

Thus the oil limits or restricts the quantity of air which can enter the system through the cylinder-port by blocking the hole or aperture more or less by reason of its resistance to such action or travel.

Ordinarily, the small or metered hole 32 should be located in the system as near the piston as practicable, so that, when the cylinder-port is again covered, only a small amount of air will have to be removed from the space between the metered hole and the piston to apply an adequate suction on the piston channel.

In Figures 4 to 8 inclusive, the invention

has been shown as incorporated in a sleeve-type of internal-combustion motor.

The piston 61 has the same kind of transverse, external, oil-collecting channel 62 equipped with the bleeder or air-inlet port 63 diametrically opposite the cylinder port 64 which is connected up to the rectifier in the same manner, but in this instance, such port has no plug or small metered hole.

10 A longitudinal slot 65 is provided in the outer, reciprocatory sleeve 66 and is of sufficient length to register always and be in continuous communication with the cylinder-port.

15 The cooperating inner sleeve 67 has the metered hole 68 through it which constantly connects with the cylinder-port through the outer sleeve port, the inner end of the metered hole next to the piston being enlarged and elongated at 69 to prolong the period the suction is applied to the piston channel and to afford a cavity for the collection of oil from the piston, which oil, as in the previous instance, acts in a measure to clog the metered hole more or less temporarily when the piston uncovers the hole, hence reducing and limiting the amount of air which will be admitted under such circumstances.

20 30 The manner in which this embodiment of the invention operates will be obvious from what precedes and requires no further elucidation.

35 In both instances, the cylinder and piston, or the cylinder, piston and sleeves, are lubricated in any approved manner, as by the well-known splash system.

40 It is to be remembered, however, that this invention is not confined to the precise structural details presented and that the invention is susceptible of a variety of embodiments varying in mechanical structure but all incorporating the underlying principles of the invention and having its main or principal benefits and advantages.

45 I claim:

50 1. In an internal-combustion engine, the combination of an engine-cylinder, a reciprocatory piston in said cylinder covering and uncovering a port during its sliding movements, means to lubricate said cylinder and piston, and means to remove fluids from around said piston through said port while the latter is covered by the piston, said port being open when uncovered by the piston.

55 2. In an internal-combustion engine, the combination of an engine-cylinder, a reciprocatory piston in said cylinder, means to lubricate said cylinder and piston, an oil-rectifier, means connecting said rectifier with a port covered and uncovered by the sliding movements of said piston, and means connecting said oil-rectifier with the intake-manifold of the engine, whereby the suction therein withdraws fluids from around said

60 piston when the latter covers said port and delivers them into the rectifier, the connection through said port to the rectifier and the intake-manifold being open when the piston uncovers said port but of such restricted size as not to permit substantial interference with the engine carburation by the admitted air.

65 3. In an internal-combustion engine, the combination of an engine-cylinder, an externally, transversely, channeled reciprocatory piston in said cylinder, means to lubricate said cylinder and piston, said engine having a port covered and uncovered by the sliding movements of said piston, the channel of the latter being in communication with said port when the piston is substantially at its lower dead center, and means to remove the contents of said piston channel through said port when said channel and port are in communication, said port being open when uncovered by said piston.

70 4. In an internal-combustion engine, the combination of an engine-cylinder, a piston reciprocatory in said cylinder, means to lubricate said cylinder and piston, said engine having a port with a flaring mouth covered and uncovered by the sliding movements of said piston, and means to remove fluids from around said piston through said port while the latter is covered by the piston, said port being open when uncovered by the piston.

75 5. In an internal-combustion engine, the combination of an engine cylinder, an externally, transversely, channeled piston reciprocatory in said cylinder, means to lubricate said cylinder and piston, said engine having a port with a flaring mouth covered and uncovered by the sliding movements of said piston, the channel of the latter being in communication with said port when the piston is substantially at its lower dead center, and means to remove the contents of said piston channel through said port when such channel and port are in communication, said port being open when uncovered by said piston.

80 6. In an internal-combustion engine, the combination of an engine-cylinder, an externally, transversely, channeled piston reciprocatory in said cylinder, means to lubricate said cylinder and piston, an oil-rectifier, means connecting said rectifier with a port having a flaring mouth covered and uncovered by the sliding movements of said piston, and means connecting said oil-rectifier with the intake-manifold of the engine, whereby the suction therein withdraws fluids from said piston channel when the latter is in communication with said port when the piston is substantially at its lower dead center and delivers them into the rectifier, the connection through said port to the rectifier and intake-manifold being open when the piston

uncovers said port but of such restricted size as not to permit substantial interference with the engine carburetion by the admitted air.

5. In an internal-combustion engine, the combination of a ported engine-cylinder, a movable sleeve in said cylinder having a port therethrough adapted to communicate with said cylinder port, a reciprocatory piston in 10 said sleeve whose sliding movements cover and uncover said sleeve port, means to lubricate said cylinder, sleeve and piston, and means to remove fluids from around said piston through said sleeve and cylinder ports 15 when the piston covers said sleeve port, the latter being open and in communication with said cylinder-port when uncovered by the piston.

8. In an internal-combustion engine, the combination of a ported engine-cylinder, a movable sleeve in said cylinder having a port therethrough adapted to communicate with said cylinder port, a reciprocatory piston in said sleeve whose sliding movements 25 cover and uncover said sleeve port, means to lubricate said cylinder, sleeve and piston, and means connecting said cylinder port with the intake-manifold of the engine whose suction removes fluids from around 30 said piston through said sleeve and cylinder ports when the piston covers said sleeve port, the latter being open and in communication with said cylinder-port when uncovered by the piston but of such restricted size as to 35 prevent substantial interference with the engine carburetion by the admitted air.

9. In an internal-combustion engine, the combination of a ported engine-cylinder, a movable sleeve in said cylinder, a reciprocatory piston in said sleeve, said sleeve having a port therethrough adapted to communicate with said cylinder port and having a flaring mouth covered and uncovered by the sliding movements of said piston, means to 40 lubricate said cylinder, sleeve and piston, and means to remove fluids from around said piston through said sleeve and cylinder ports when the piston covers said sleeve port, the latter being open and in communication with 45 said cylinder-port when uncovered by the piston.

10. In an internal-combustion engine, the combination of a ported engine-cylinder, a movable sleeve in said cylinder, a reciprocatory piston in said sleeve, means to lubri- 50

cate said cylinder, sleeve and piston, said sleeve having therethrough a port with a flaring mouth covered and uncovered by the sliding movements of said piston, said sleeve port being adapted to communicate with said cylinder port, said piston having an external transverse channel which comes into communication with said sleeve port when the piston is substantially at lower dead center, said piston having an air inlet port at a point 60 remote from said sleeve port, an oil-rectifier, means connecting said oil-rectifier to the cylinder port, and means connecting said rectifier with the intake-manifold of the engine whose suction withdraws fluids from said 65 piston channel through said sleeve and cylinder ports into said rectifier, said sleeve port being open and in communication with said cylinder-port when uncovered by the piston but of such restricted size as to prevent substantial interference with the engine carburetion by the admitted air. 70

11. In an internal-combustion engine, the combination of an engine-cylinder, a reciprocatory piston in said cylinder covering and uncovering a port during its sliding movements, means to lubricate said engine, and means to apply suction to said port to remove fluids from around said piston when the latter covers said port, such port being 85 of sufficiently restricted caliber to limit the amount of air passing therethrough when the port is uncovered by the piston to permit the suction to operate as specified. 90

12. In an internal-combustion engine, the combination of an engine-cylinder, a reciprocatory piston in said cylinder, means to lubricate said cylinder and piston, means connecting the intake-manifold of the engine with a port covered and uncovered by the 95 sliding movements of said piston, whereby the suction of such manifold withdraws fluids from around said piston when the latter covers said port, the connection through said port to the intake-manifold being open 100 when the piston uncovers said port but of such restricted size as not to permit substantial interference with the engine carburetion by the admitted air, and means to return the withdrawn oil to the lubrication system of 105 the engine.

In witness whereof I have hereunto set my hand.

RALPH L. SKINNER.
